UNITED STATES PATENT OFFICE.

BENJAMIN F. GRISCOM, OF PHILADELPHIA, PENNSYLVANIA.

KEY-PURSE.

SPECIFICATION forming part of Letters Patent No. 689,872, dated December 31, 1901.

Application filed May 1, 1901. Serial No. 58,300. (No model.)

To all whom it may concern:

Be it known that I, BENJAMIN F. GRISCOM, a citizen of the United States, whose residence is 1413 North Sixteenth street, Philadelphia, 5 county of Philadelphia, State of Pennsylvania, have invented certain new and useful Improvements in Key-Purses, fully described and represented in the following specification and the accompanying drawings, forming a 10 part of the same.

It is common for many persons to use a key ring or chain to secure a number of keys together, and such connection prevents their loss and enables them to be readily found 15 when carried in a pocket with other articles. A knife, various kinds of charms, smoker's utensils, and other requisites for a gentleman's use are often attached to the ring with the keys, and some of such articles are sometimes 20 of considerable value and liable to be seriously injured by rust or dampness.

My invention comprises a species of flat purse adapted to inclose the keys when in the pocket and closed at the sides and at one end, 25 with an opening in the other end adapted to slide upon the key-chain, the opening at the opposite end being provided with a suitable catch to retain the keys in the purse when desired, but when loosened permitting the 30 purse to be slid upward upon the chain, and thus offer no interference to the free manipulation and use of the keys separately. The purse is made of two oblong pieces of yielding material, as leather, sewed together upon 35 the sides and at one end exposing the opening for the key-chain and with the loose flaps at the opposite end connected by a snap-button. If the keys were inclosed in the purse without a chain, the purse and keys 40 could be stolen from the pocket, but by my construction the ordinary key-chain can be used, which has its outer end attached firmly to the clothing to prevent the theft of the keys, and the purse can at pleasure be slid 45 upward upon the chain to use the keys as freely as if no purse were employed.

The invention will be understood by reference to the annexed drawings, in which—

Figure 1 is a side elevation of the purse 50 with opening at one end for the free passage of a chain, the keys being shown inside the purse with a portion of the ring and chain

projecting outside of the opening, and the flap at the opening of the purse turned backward to show the snap-button. Fig. 2 is an 55 edge view of the same purse with keys inside and the opening closed by the fastener, and Fig. 3 is a side view of the purse with a chain-loop attached to the end of a chain for securing the keys and the keys concealed by 60 the purse. Fig. 4 shows the same construction of purse with the chain drawn into the opening sufficiently to remove the keys from the purse. The opening formed by the loose flaps or edges of the leather is shown in Figs. 65 1 to 4, inclusive, at the lower end or apex of the purse, and Figs. 3 and 4 are drawn upon a smaller scale than the preceding figures.

The two side pieces of the purse are preferably made of leather, as the metal articles 70 inclosed are liable to speedily chafe and wear any other substance, and such material maintains the shape of the purse without the need of any metallic frame, and thus furnishes a light and efficient construction. The sides 75 *a a'* are shown in Figs. 1 to 4 united at each of two opposite edges by a row of stitches *b*, leaving a small opening *c* in the top for the passage of a chain and a larger opening or mouth at the bottom for the insertion and removal of the bunch of keys. The stud *d* and socket *e* of a snap-button are shown upon the back and front flaps of the large opening and keep the mouth closed when desired. Two segmental pieces *f* are shown stitched around 80 the upper opening *c* to reinforce the same, so as to preserve its strength where chafed by the passage of the chain. A key-ring *g* is shown in Fig. 1 with keys *h* thereon and a chain *l* attached to the ring and extended 85 outside of the purse. By opening the fastener and pressing the edges of the purse the mouth is opened so that the keys may readily be dropped out of the same, the chain at the same time being dragged through the opening *o*, as is shown in Fig. 4.

Figs. 3 and 4 show the purse with the same construction as in Fig. 1, but the keys attached to a loop of chain *j* instead of to a key-ring, the ends of such loop being secured detachably to the chain *l* by a snap-hook or ring *k*. By inspection of Fig. 4 it will be seen that the keys may be readily drawn into the purse by pulling the chain upward with 90 95 100

one hand when the purse is held in the other, the fastener then serving to secure the keys inside. The free end of the chain *l* is for gentlemen's use commonly provided, as shown 5 in Fig. 3, with a loop *m* for attachment to the trousers-button, and as the opening at the top of the purse is not large enough to withdraw the key-ring or keys the purse is held securely upon the chain. By such a loop or 10 other suitable means the outer end of the chain may be secured to the clothing, so that the keys cannot be stolen or the purse containing the same, and the keys are thus securely held while the purse protects them 15 from abrading the pocket and from any injurious effects of dust or dampness.

It is common to make a key-purse with a large opening at the side and a snap-hook at the middle of such opening with a post in one 20 end of the purse and a key-ring thereon to retain the keys inside the purse. Such a purse is not adapted to retain the keys without attachment to the key-ring and the post, as the side opening requires to be very large 25 to render the keys accessible when the fastening is loosened. In my construction the closing of the purse at its longitudinal edges retains the keys therein when the end opening is secured by the fastening *d*, and my 30 construction thus secures the keys in the purse when desired and permits of their instantaneous removal when required.

I hereby disclaim a key-purse having the key-ring secured within the purse by any 35 means, as the sliding of my purse upon the

key-chain enables the owner to use the articles separately with a great deal more convenience than if hinged to the purse.

Having thus set forth the nature of the invention, what is claimed herein is— 40

1. The combination, with the key-chain and means for attaching the keys thereto, of a key-purse of oblong form closed upon the sides and upon one end with a small opening at such end applied to the chain, and larger 45 opening at the other end to admit the keys, with fastening at such larger opening to close the same and retain the keys in the purse, whereby when the fastening is loosened the purse is movable upon the chain to withdraw the keys entirely from the purse.

2. The combination, with the key-chain and means for attaching the keys thereto, of a key-purse comprising two oblong pieces of leather joined at the two longitudinal sides 55 and at one end, with an opening at such end applied to the chain, and reinforced about such opening to resist the wear of the chain, the opposite end being open to admit the keys and provided with a fastening, whereby 60 when the fastening is loosened the purse is movable upon the chain to withdraw the keys entirely from the purse.

In testimony whereof I have hereunto set my hand in the presence of two subscribing 65 witnesses.

BENJAMIN F. GRISCOM.
